CLAIM

The ornamental design for a camera mount, as shown and described.

DESCRIPTION

FIG. 1 is a front, upper, left perspective view of an embodiment of a camera mount of our new design in a first state; FIG. 2 is a front view thereof; FIG. 3 is a rear view thereof; FIG. 4 is a left view thereof; FIG. 5 is a right view thereof; FIG. 6 is a top view thereof; FIG. 7 is a bottom view thereof; FIG. 8 is a front, upper, left perspective view thereof in a second state; FIG. 9 is a front view thereof; FIG. 10 is a rear view thereof; FIG. 11 is a left view thereof; FIG. 12 is a right view thereof; FIG. 13 is a top view thereof; and, FIG. 14 is a bottom view thereof.

The broken lines shown in the figures depict portions of the camera mount that form no part of the claimed design.

1 Claim, 12 Drawing Sheets
